UNITED STATES PATENT OFFICE.

ROBERT MURPHY, OF PASSAIC, NEW JERSEY, AND HERMAN DEUTSCH, OF NEW YORK, N. Y.

COMBINED HANDKERCHIEF AND POWDER-PUFF.

1,180,869.

Specification of Letters Patent. Patented Apr. 25, 1916.

Application filed March 15, 1915. Serial No. 14,428.

To all whom it may concern:

Be it known that we, ROBERT MURPHY, a subject of the King of England, residing in Passaic, county of Passaic, and State of New Jersey, and HERMAN DEUTSCH, a citizen of the United States, residing in the city, county, and State of New York, have invented certain new and useful Improvements in Combined Handkerchiefs and Powder-Puffs; and we do hereby declare the following to be a full, clear, and exact description of the invention, such as will enable others skilled in the art to which it appertains to make and use the same.

15 The present invention relates to handkerchiefs and has for its object the provision of a handkerchief with a part particularly adapted to serve as a powder puff.

In one embodiment there is permanently secured to one face of an ordinary handkerchief, a pad of powder retaining material, which may be a fabric with a high nap, or may be of other special material particularly adapted for use in applying and distributing 25 face powder while at the same time being capable of laundering. In another embodiment, the powder retaining material is woven in on the loom, as a part of the fabric, and its high nap may be arranged in 30 ornamental design on the handkerchief in accordance with known methods of weaving special patterns.

The article as a whole, whether having the pad permanently stitched to the face of ordinary handkerchief material, or woven directly therein, can be laundered as if it were an ordinary handkerchief, and so may be maintained in hygienic condition, and offers the further advantage that by its use the 40 powder may be applied unobtrusively.

Other details and advantages will be made clear by the following description, which is to be taken in conjunction with the accompanying drawings, wherein—

45 Figure 1 is a perspective view of a handkerchief complete with the powder applying pad; Fig. 2 is a sectional view through the pad showing one mode of stitching it to the handkerchief; and Fig. 3 shows a modification wherein the pad is woven in as a part of the fabric.

The handkerchief shown in Figs. 1 and 2 is of usual size and material, and the powder retaining pad 2 is permanently secured 50 to one face thereof by stitching or the like,

preferably near one corner of the handkerchief. The stitching 3 may be of ornamental character, such as buttonhole stitching, done with silk, and when the stitching is of this character, the pad is firmly attached along 60 its entire border and the finished article is substantial in character and presents a pleasing appearance.

The pad itself consists of a washable fabric having a high nap, such, for instance, as 65 canton flannel, cotton plush, and similar materials, suitable for use in applying face powder, and when so constituted, offers no impediment to laundering and sterilization by boiling.

70 In the modification shown in Fig. 3, the pad is formed from material woven in at the time the handkerchief is made, this material having the desired high nap to form a powder retaining pad and being of a size and 75 shape adapted for this purpose. It may be heart-shaped or of irregular design, and may be positioned near the corner of the handkerchief as shown.

A combined handkerchief and powder 80 puff constructed as above described, can be carried as easily as an ordinary handkerchief, tucked away in a convenient place, and the powder puff, virtually concealed in the corner of the handkerchief, may be used as 85 often as necessary without annoyance or embarrassment to the owner.

It will be seen that by making the pad of relatively small size, and of an area less than one fourth the area of the handkerchief, the 90 handkerchief can be folded in the middle in both directions, as usual, and both sides of the handkerchief are also free and unobstructed for use except for the pad section near one corner. Accordingly, the handkerchief is capable of use on both sides, in the usual manner, except for the relatively small pad section; while the provision of this pad further adapts the handkerchief to serve as 95 an improved powder puff, as above indicated.

100 Although the drawings illustrate a suitable arrangement of the powder retaining pad on the handkerchief, we are aware that the pad may be otherwise positioned on the handkerchief, and that its size and shape 105 and the ornamental character of its attachment may be varied in many ways.

We claim:

110 1. A handkerchief having a relatively

- small pad of washable fabric permanently and directly secured thereto and having an area less than one fourth the area of the handkerchief, whereby both sides of the handkerchief are free and unobstructed for use except for said pad section, said pad being of soft powder-retaining material and adapted to serve as a powder puff and to be laundered as a part of the handkerchief.
2. A handkerchief having a relatively small pad of washable fabric permanently and directly stitched to the handkerchief around its edges and having an area less

than one fourth the area of the handkerchief, said pad being of soft material with a 15 high nap and adapted to serve as a powder puff and to be laundered as a part of the handkerchief.

In testimony whereof we affix our signatures.

ROBERT MURPHY,
HERMAN DEUTSCH.
